UNITED STATES PATENT OFFICE.

D. C. McCALLUM, OF OWEGO, NEW YORK.

MEANS FOR ADJUSTING THE EFFECTIVE LENGTH OF BRIDGE-COUNTERBRACES.

Specification of Letters Patent No. 8,224, dated July 15, 1851.

To all whom it may concern:

Be it known that I, D. C. McCALLUM, of Owego, in the county of Tioga and State of New York, have invented certain new and useful Improvements in Bridges, which are also Applicable to Girders for any Purpose; and I do hereby declare that the following is a full, clear, and exact description of the same, reference being had to the accompanying drawings, forming part of this specification, in which—

Figure 1 is a longitudinal elevation of a bridge girder. Fig. 2 is a longitudinal vertical section of part of the same. Fig. 15 3 is a plan of part of the upper chord. Fig. 4 is a transverse section through the line $x-x$ in Fig. 1. Figs. 5 and 6 represent the counter braces, on a scale larger than the other figures.

20 Similar letters of reference indicate corresponding parts in each of the several figures.

My invention relates to the construction of open built beams or girders employed in 25 bridges, and other structures of a similar nature.

My improvement consists in a new method of lengthening, or shortening the counter braces, whereby I am enabled to 30 produce and maintain any required downward vertical strain, or deflection, upon the girders, and which method I deem far more useful in practice than those sometimes employed of using gibs and keys, or wedges for 35 that purpose.

A, represents the lower chord of the girder, composed of four or of any suitable number of string pieces bolted together—and having cleats α , α , placed between them 40 at suitable distances. It is nearly straight, having only a very slight camber. B, is the upper chord, formed also of any suitable number of stringers, and is of an arched form. The two chords are connected by 45 posts C, C, forming radii to the upper chord, and also at their ends, by vertical posts E, E, all of the said posts being so connected with the chords as to maintain the required positions of the several parts.

50 D, D, are thrust braces, each notched into the top of one of the posts C, C, and into the foot of the next post nearer the end of the girder.

F, F, are inclined ties, or tension rods, 55 outside the girder.

G, G, are ties, or tension rods, similar to

F, F, passing through the lower and upper chords of the girder, at about the middle of its thickness.

The several parts of the girder, as far as I have described them, do not differ, essentially, in their construction and arrangement from those of some other girders in use. Each of the ties or tension rods last described, G, is incased by a counter brace H, 60 the lower part of which is of wood, and may be either in one piece, bored through, to admit the rod, or in two pieces, placed one on each side of the rod; the lower end abutting on a step b , placed on the lower chord, 65 at the foot of the posts C, and its upper end fitted to a metallic sheath I, through which also the tension rod passes. This sheath, which is best shown in Figs. 5 and 6, consists of a tube having at its lower end a 70 socket into which the top of the counter brace H, is fitted. The tension rods pass through clamping pieces c , c , under the lower chord, and others c' , c' , above the upper chord. These clamping pieces bear 75 also against the head and foot of the posts C, C. The upper end of the sheath passes through the clamping piece c' , and is of sufficient length to project a short distance 80 above it. A plate of metal, d, having a hole 85 through it of just sufficient size to pass the rod G is attached, at the top of the girder, by bolts e, e, which pass through the clamping pieces, the upper chord, and the posts C, C, in a direction parallel with the tension rods. This plate bears on top of the 90 sheath I.

J, is an arched beam, placed immediately below the upper chord B, and notched between the posts C, C. It extends from the 95 crown of the arch about half way to the ends.

K, K, are inclined struts, the upper ends of which abut against the ends of the arched timber J. They are secured by bolts f, f to 100 the posts C, C, between which they pass, being also notched into the posts. They also pass through the lower chord A, and the bolsters L, L, and rest in seats, on the top of the abutments or piers.

M, M, are other inclined struts, their upper ends abutting against steps g, g, under the upper chord B. They are secured to the posts, and pass through the lower chord and bolsters, and rest upon the abutments or 110 piers, in a similar manner to K, K. Those counter braces H H which come in the way

of the inclined struts, are in pieces, notched into the struts. The tension rods pass through them.

N, represents part of an abutment. O, a pier. P, P, are the roadway bearers, supported on the top of the posts, C, C, which are continued, above the upper chord. These bearers may however be secured to the posts and to the thrust braces, D, D, at any height either above or below the upper chord.

In erecting the bridge, all the parts are put together, and all except the tension rods G, G, and bolts, e, e, are bolted or screwed up. The bridge should then be loaded with a weight, greater than it will ever be required to bear, in ordinary traffic. It has been stated, in the foregoing description, that the length of the counter braces, is such, as to allow the ends of the metallic sheaths I, I, to project through the clamping pieces, c', c'. This projection should be such, that the deflection of the girders, caused by the weight on the bridge, will, by increasing the distance between the steps b, b, and the clamping pieces c', c', cause the ends of the sheaths, to stand exactly flush, or a little above, the face of the clamping pieces. The plates, d, d, are then screwed down, to bear on the end of the sheaths, by means of the nuts and the bolts e, e, by which the deflection, produced by the load is maintained, after the load shall have been removed. The nuts on the ties or tension rods—G, G, may then be screwed up, to bring the required degree of tension upon them.

The braces H, H might be continued through the upper chord of the girder, but the metallic sheath I, is better suited, as it

can be much smaller, and is not so liable to 40 injury at its end.

It is obvious that, whenever a strain or deflection, has been produced, and is maintained upon a girder, in the manner stated, any weight less than the one producing the 45 deflection, may be brought upon it, without increasing the strain, or deflection, and consequently the girder will not be subjected to any vertical vibration, by the passing of this lesser weight over it. Wedges have been 50 used, to effect this desirable object, but as they are liable to become loose, and work out of place, an effectual remedy and substitute is above described.

What I claim as my invention, and desire 55 to secure by Letters Patent, is—

The method of lengthening or shortening the counter braces of a girder or bridge truss, so as to produce and maintain any desired, vertical strain, or deflection, of the 60 girder or truss by means of the counter brace H, whether all of wood or provided with a metallic end or sheath; the plate of metal d, bearing, upon the metallic end or sheath, (or upon the end of the wood, when 65 the metallic end or sheath is not used) at the top of the girder; and the nuts, and the bolts e, e, passing through the clamping pieces, c, c, the upper chord, and the posts, by 70 which the plate of metal d, is drawn down upon the metallic end or sheath and the adjustment of the length, of the counter brace is effected, substantially as herein described.

D. C. McCALLUM.
